UNITED STATES PATENT OFFICE.

DONALD C. WOODWORTH, OF AUBURN, MAINE.

ANTISKID-CHAIN TOOL.

Application filed April 17, 1922. Serial No. 553,941.

To all whom it may concern:

Be it known that I, DONALD C. WOODWORTH, a citizen of the United States, residing at Auburn, in the county of Androscoggin and State of Maine, have invented 5 certain new and useful Improvements in Antiskid-Chain Tools, of which the following is a specification.

My invention relates to the tools of this 10 sort which are described in U. S. Patent No. 1,338,804 which was issued to me on the fourth of May, 1920. In the use of tools made in accordance with the specification of the above patent, it is found that when 15 they are properly proportioned for opening the smaller sizes of fastening links, they are unsuitable for opening links that are either very much longer or very much stiffer.

20 The object of my invention is to provide a tool which is equally well adapted to opening widely differing sizes of links.

To attain this object, I provide as herein-after specified, new means of attachment for 25 different sizes of links. I rearrange the parts so as to give a greatly increased leverage for the same size of tool; and I provide for a new mode of operation which divides the opening of the larger sizes of links into 30 two or more steps. In the accompanying drawings;

Fig. 1 is a perspective of the tool with a completely opened link attached.

Fig. 2 shows the tool ready for closing 35 a link.

Fig. 3 shows the opening of a long link.

In these figures, 1 and 2 are the two 40 pivotally connected, handled members which make up the tool. 3 and 4 are the opening hooks projecting from the side of the member 1. 5 is an opening wedge projecting from the upper end of the member 2. 6 is the pivot on which the members 1 and 2 turn. 7 is a closing jaw projecting from the 45 side of the member 2. 8 is a corresponding jaw projecting from the side of the member 1. By placing the closing jaws at the sides of the members 1 and 2, I make it possible to bring the opening wedge 5 much 50 more nearly in line with the pivot and opening hook, and thereby greatly increase the leverage of the device. 9 is the link to be opened and closed; 10 is another chain link.

When I wish to make use of my invention 55 for opening one of the smaller sizes of the links 9, I hook it over the opening

wedge 5 at the end of the member 2 and pull apart the handle ends of 1 and 2 until the loop end of the link 9 will slip over the opening hook 3, I then press together the 60 handle ends of 1 and 2 until the link is fully opened.

The range of motion of the members 1 and 2, when grasped by the hand, is sufficient to provide for opening the smaller 65 sizes. If bringing 1 and 2 into the position of Fig. 1 does not fully open the link 9 I pull the handle ends of the members 1 and 2 apart, and hook the link over the 70 hook 4. If closing the handle ends of the tool still fails to fully open the link 9, I pull them apart again and slip the link 10 between 4 and 9 as shown in Fig. 3, and repeat the compression of the handles.

As, in this way of working, the handle 75 ends of 1 and 2 are never spread far apart, they have at all times a great leverage and will pry open links that would prove too stiff if the members 1 and 2 made a wide angle with each other.

If it is desired to extend the range of the device, one or more opening hooks may be added below the hooks 3 and 4; but the device as shown will cover a wide range.

The device as shown is properly proportioned for the work specified, but it is also usable and will be used as an ordinary pair of pliers. I therefore cut sharp teeth in the jaws 7 and 8 and give them greater hardness, and the tool greater strength than 90 would otherwise be necessary.

Having thus described my invention, what I claim is—

1. In a tool for opening the fastening links of antiskid-chains, the combination 95 with a pair of pivotally connected members, of an opening wedge projecting from the working end of one of the members, and a plurality of opening hooks on the handle end of the other member, which are spaced 100 at distances from the wedge corresponding to the different lengths of fastening links.

2. In a tool for opening and closing the fastening links of antiskid-chains, a pair of pivotally connected members, a pair of 105 closing jaws which are bent in the same direction and have their line of action at the side of the tool, an opening wedge at the end of one member and an opening hook which projects from the handle of the other 110 member, all combined with each other for the purpose specified.

3. In an antiskid-chain tool which has a pair of pivotally connected handled members, an opening wedge on one member, an opening hook on the other member which is spaced at a distance from the wedge corresponding to a partial opening of the link, and a second opening hook spaced at a greater distance from the wedge; all com-

bined with each other for the purpose specified.

In testimony whereof I affix my signature.

DONALD C. WOODWORTH.
